UNITED STATES PATENT OFFICE.

WILLIAM BAUMGARTEN, OF BALTIMORE, MARYLAND.

DESIGN FOR A BUTTON OR SIMILAR ARTICLE.

SPECIFICATION forming part of Design No. 31,061, dated June 27, 1899.

Application filed May 18, 1899. Serial No. 717,366. Term of patent 31 years.

To all whom it may concern:

Be it known that I, WILLIAM BAUMGARTEN, a citizen of the United States, residing at Baltimore city, in the State of Maryland, have 5 invented and produced a new and original Design for Buttons or Similar Articles; and I do hereby declare the following to be a full, clear, and exact description of the same, reference being had to the accompanying drawings, forming a part thereof.

My invention relates to buttons or similar articles; and it consists in a button having the representation of an ax-head in perspective upon a plain convexed disk forming the 15 face of the button, the ax-head having a space or interval across its face, and showing the eye of the ax.

In the accompanying drawings, illustrating my new design, Figure 1 is a face view of the 20 button, and Fig. 2 is an edge view thereof.

The leading feature of my design consists of a button having the representation of an

ax-head upon a convexed disk forming the face of the button, the ax-head having a space or interval across the face thereof.

25

In the drawings, A denotes the plain convexed disk, which forms the face of the button or similar article; B, a heavy solid border around the disk; C, the ax-head, and D the space or interval across the face of the ax-head, adapted to contain letters or words, as desired, said button having a shank E.

30

Other similar articles—such as pins, studs, and ornaments—may be formed of the said design.

35

What I claim is—

The design for a button or similar article herein shown and described.

In testimony whereof I affix my signature in presence of two witnesses.

WILLIAM BAUMGARTEN.

Witnesses:

JOSEPH C. SMITH,
JOSEPH SIMON.
